UNITED STATES PATENT OFFICE.

GEORGE E. BENNITT, OF NEW YORK, N. Y., ASSIGNOR TO PEERLESS MANUFACTURING COMPANY, OF LOUISVILLE, KENTUCKY, A CORPORATION OF DELAWARE.

RADIANT GAS HEATER.

Application filed January 21, 1925. Serial No. 3,719.

To all whom it may concern:

Be it known that I, GEORGE E. BENNITT, a citizen of the United States, residing at New York, in the county of New York and 5 State of New York, have invented a certain new and useful Improvement in Radiant Gas Heaters, of which the following is a full, clear, and exact description, reference being had to the accompanying drawings.

This invention relates to gas heaters of the class known as radiant or mantle heaters wherein hollow foraminous radiants or mantles of refractory material are disposed 15 above the ports or openings of a Bunsen burner and are rendered incandescent by the flame ascending through them.

Heaters of this class are highly efficient and satisfactory when all conditions affecting their operation are right. Heretofore, 20 the basic factor in a successful performance of such a heater was the character or quality of the gas, and if this factor were constant, and the heater was designed especially for use with a gas of given character, such as natural gas or a manufactured gas of substantially fixed properties, there was more than reasonable assurance that the 25 results would be satisfactory. Under these circumstances it was necessary to produce distinctly different burners for natural and manufactured gas, respectively, and, as to the latter gas, this only partially solved the 30 problem as there is a wide variation in the character of manufactured gas. To begin with, manufactured gas differs from natural gas in heating value, specific gravity, pressure and chemical composition; and the different kinds of manufactured gas, such as 35 coal gas, water gas, and coke oven gas differ from each other in the same respects.

The diminishing supply of natural gas has resulted in extensive use of a mixture of natural and manufactured gas and since the 45 issue of natural gas is limited, the proportions of the two gases change in accordance with the demand, the larger the demand the greater the proportion of manufactured gas.

From the foregoing it will be seen how utterly impracticable it would be to construct heaters individually suited to the many grades of gas, and as a consequence it is now purely a coincidence if a heater

is adapted to the kind of gas that is used 55 in it, wherefore it is the exception rather than the rule that a radiant heater is efficient and satisfactory.

Of even greater concern than efficiency is the matter of health and safety. Unless 60 the conditions are ripe and the gas is completely burned inside the radiants, the heaters give off carbon monoxide and other noxious gases. Due to this situation, much 65 adverse criticism has been uttered against radiant or mantle gas heaters.

It is the primary purpose of my invention to produce a burner for radiant heaters that is, in a sense, of universal adaptability, 70 being suitable for use with either natural or manufactured gas, or a mixture of the two in any proportions, and which is highly efficient and safe under all conditions arising within the scope of its intended use.

Other objects in view are to provide a 75 burner for radiant or mantle heaters which is so designed and constructed as to effect a uniform distribution of the gas to all burner ports; to obviate backfiring into the mixer; and to cause the flame to rise centrally within the radiants so that the radiants are heated at the top as well as at the bottom and a uniform distribution of heat over the whole heating surface is obtained.

Another factor contributing to the successful operation of the heater is a definite relation between the size of the radiant and the heating value of the gas. I have found through observation and experimentation 90 that a radiant of standard size requires for the purpose of maintaining it incandescent the burning of a quantity of gas producing substantially 1800 British thermal units per hour. To effect this result with gases of different properties I provide an adjustment for the gas emitting orifice of the burner which is separate from the gas supply control.

As the primary air required to give rapid 100 combustion and high flame temperature—as indicated by the sharp blue inner cone which is a characteristic of Bunsen flames—varies with the chemical composition of the gas, I provide, in combination with the other features of my improvements, a suitably adjustable air shutter by means of which the primary air supply may be

changed at will to suit the wide range in chemical composition of the various gases.

As the secondary air controls, to a large extent, the escape from the radiant or mantle of carbon monoxide and other noxious gases, it must be properly restricted; too much secondary air chilling a portion of the flame within the radiant thus keeping it below the ignition temperature, and too little causing a floating flame a portion of which is chilled outside the radiant, either of which conditions will cause the escape of noxious gases into the room. This proper control of secondary air is effected by positioning the radiant in a definite relation to the burner so as to provide an air opening between the radiant and the adjacent portion of the burner that is in correct relation or proportion to the area of the burner port or ports leading into the radiant.

I find that better results are obtained by using a multiple or double jet Bunsen flame instead of a single jet as it affords a better secondary air distribution. However, to meet the requirements of the different kinds of gases that are in general use, the jets have to be separated a material distance apart as otherwise, with natural or other gases containing a large percentage of slow burning constituents, such as methane in natural gas, such gases producing comparatively large flames, the cones of the two jets merge and thus shut out the intermediate secondary air space and cause a "floating flame" with a resultant escape of noxious gases.

While it is highly desirable, therefore, to use a multiple jet Bunsen flame, and separate the jets as described, measures have to be taken to avoid contact of the inner cones of the flame with the radiant as this would arrest combustion and cause an escape of unburned noxious gases. To obviate this I arrange the ports for each radiant on upwardly converging axes which intersect a definite distance above the outlet ends of the ports on a line centrally between them and perpendicular to the plane of said outlet ends; and I further incline the ends of the ports inwardly and upwardly so as to deflect the ends of the jets away from the walls of the radiants.

From what has thus far been said it will be seen that in the evolving of my invention with the definite end in view of producing a radiant or mantle heater that is adapted for use with all commercial gases, the specific objects are to provide a Bunsen burner for use with radiants having a multiple or double jet gas supply for each radiant, the gas supply ports being properly spaced apart to avoid merging of the inner cones of the flame and to provide proper secondary air supply and distribution; and to so shape and converge the ports as to avoid

contact of the inner cones with the radiant to provide a proper secondary air supply about and between the jets as by spacing the radiant a proper distance from the burner and, as will hereinafter appear, by forming the burner body with an air passageway between opposed ports; to provide, in combination with the foregoing, an adjustable control for the primary air; and, in order to create the required relation between the heating value of the gas and the size of the radiant, to provide an adjustable gas emitting orifice.

With the nature and purposes of the invention thus set forth I shall now specifically describe the same by reference to the accompanying drawings wherein Fig. 1 is a vertical section from front to rear through a heater embodying the invention; Fig. 2 is a sectional front elevation of the burner, with fragments of a fireback and radiants associated with it, the planes of the sectional portions of the view being indicated by the line 2-2 of Fig. 3; Fig. 3 is a plan view of the burner, with a part of the fireback and sections of radiants shown at the right hand end of the view; Figs. 4 and 5 are sectional views, on a considerably enlarged scale, through the burner, the planes of the respective sectional views being indicated by the lines 4-4 and 5-5 of Fig. 3; Fig. 6 is a sectional detail of the gas control valve; Fig. 7 is a longitudinal sectional view through a mold used in the casting of the burner; and Fig. 8 is a transverse section through the same, the scales on which these views are drawn corresponding, respectively, to those of Figs. 2 and 4.

My improvements are applicable to practically all styles or designs of radiant heaters, a representative type being shown in Fig. 1. The heater comprises an open front casing 1 within the lower portion of which is supported my improved burner 2, the same being formed with ears 3 at its opposite ends by means of which it may be bolted or otherwise secured to the end walls of the casing.

The burner is cast in the form of a loop having front and rear branches 5 and 6, respectively, which are hollow and communicate with each other at both ends. Burner openings or ports 7 are formed in the top walls of the branches 5 and 6 and, as shown in Figs. 1 and 5, these ports are laid out on upwardly converging axes which intersect a distance above the plane of the top of the burner on a line perpendicular to said plane and substantially midway between the ports 7. As will be observed from Fig. 2, the end walls of the ports are inclined upwardly and inwardly so as to produce an upwardly convergent gas jet. The ports are spaced apart longitudinally of the burner and those of one

branch are directly opposite the ones of the other branch. The corresponding ports of the two branches constitute a pair which supply gas to a radiant, and the radiants 5 are supported directly above their respective ports by radiant supporting and positioning lugs 10. Especially from Fig. 3 it will be seen that the lugs are designed to receive the radiants with a comparatively 10 accurate fit and to support adjacent radiants very close together.

The radiants, designated 11, are preferably made of white fire clay or other suitable refractory material, and they are foraminous, having comparatively large openings 13 in their front walls, slot like openings 14 in their rear walls, and at their lower ends are provided with notches 15 in their side walls so that the flame may 20 be instantly communicated to all burner ports when a match or other igniting means is applied to any one of the radiants and the gas turned on. Protuberances 16 are formed on the front and rear walls of the 25 radiants and project inwardly a material distance, as shown in Figs. 3 and 5.

In front elevation the radiants are of substantially the same width from top to bottom while in side elevation they taper to 30 a smaller dimension at the top; and adjacent their tops, the radiants rest against a fireback 20 which is supported upon arms 21 that extend rearwardly from the burner 2 and is sustained in an upwardly and forwardly inclined position by a channel member 22 which embraces the top edge of the fireback and is secured, through a base 23 and fastening means 24, such as stove bolts, to the back of the casing 1.

Depending from the left hand end of the burner is an internally threaded boss 26 into which is screwed one end of a mixing tube 27, the tube being enlarged at its opposite end to constitute a mixer proper that 45 is designated 28. This mixer is of usual construction and is equipped with an air shutter 29 which is adapted to be secured in any adjusted position by a screw 30. Gas is supplied to the mixer 28 through a valve 50 31 which is associated in a common and well known manner with the mixer. As will be seen by reference to Fig. 6 this valve incorporates, besides the main gas control valve 32 that is adapted to be operated by 55 a handle 33, an auxiliary adjustment in the nature of a needle valve 34 which is threaded within a lateral branch 35 of the valve body, is equipped at its outer end with a knurled head 36, and cooperates with the gas emitting orifice 37 which opens into the mixer.

In fitting the heater for use, after the same is properly installed and the valve 31 connected to a gas supply pipe 40, the valve 60 32 is opened, the gas lighted, and the need-

le valve 34 adjusted to pass a quantity of gas sufficient to produce approximately 1800 B. t. u.'s per hour for each radiant; and the shutter 29 is adjusted to effect sharp and well defined blue cones over the ports 70 7. As the flame rises within each of the radiants, it is supplied with the proper amount of secondary air, a part entering between the lower end of the radiant and the burner, a part between the burner 75 branches 5 and 6, a part through the openings 13 in the front wall of the radiant, and a part through the slot like openings 14 in the rear of the radiants, the fireback 20 being fluted, as indicated at 20^a, 80 to enhance the flow of the secondary air upwardly along the backs of the radiants. Since the jets of gas issuing from the ports 7 converge so as to centralize the flames within the radiants, the partially burned 85 gas within the lower ends of the radiants is prevented from contacting with the lower parts of the walls and protuberances thereof so as not to arrest combustion at this point. By the time the gas reaches the tops 90 of the radiants it is completely burned and the products escape over the top of the fireback and between it and the top wall 41 of the casing and are carried off through the flue collar 42.

It is very essential to a satisfactory operation of the burner that the parts 7 be smooth, of uniform size, and that they be accurately arranged as hereinbefore described. If the ports were formed in the usual way when the burner is cast by simply providing extensions of the core material on the core, it would result in rough surfaces and, furthermore, because of the fragile nature of the core material, it would not be uncommon for the ports to be irregular due to crumbling or breaking of the parts of the core which were designed to produce the ports. Also the cutting or sawing of the ports is expensive and in 105 other respects objectionable and unsatisfactory.

To obviate these difficulties I fit the core which produces the chamber or cavity of the burner, with chills of suitable metal, 110 such as steel, so that the ports will be absolutely accurate and uniform as to size and arrangement, and the walls thereof will be perfectly smooth.

In Figs. 7 and 8, 45 designates the mold 120 wherein the burner is cast, and 46 the core for producing the chamber or cavity of the burner. Chills 47 are set within the upper edges of the portions of the core 46 which correspond to the branches 5 and 6 125 of the burner, and these chills are upwardly tapered, as indicated in Fig. 7, so as to produce the upwardly and inwardly inclined end walls of the ports. So that the mold may be more conveniently compared with 130

the product, as the latter is illustrated in the drawings, I have shown it in the same position although, in practice, the mold is inverted so that the core 46 rests upon the 5 chills 47, and the casting is poured from the side corresponding to the bottom of the burner through the usual sprue (not shown).

After the casting is withdrawn from the 10 mold, the core is disintegrated and removed in the usual way. The chills 47 are then projected into the chambers or cavities of the branches 5 and 6 and the casting is tilted to cause the chills to slide to the 15 end of the casting adjacent the boss 26 through which they may be discharged.

Having thus described my invention, what I claim is:

1. In combination, a Bunsen burner having a group of ports arranged relatively close together with a secondary air space between adjacent ports, and a radiant supported above the group of ports and spaced from the burner to provide a secondary air space between the lower end of the radiant and the burner.

2. In combination, a Bunsen burner having two ports and a secondary air space between said ports, and a radiant supported 30 above the ports and spaced from the burner to provide a secondary air space between the lower end of the radiant and the burner.

3. In combination, a Bunsen burner having two ports spaced a material distance 35 apart and a secondary air space between the ports, the axes of said ports converging upwardly, and a radiant supported above the ports and spaced from the burner to provide a secondary air space between the lower end of the radiant and the burner.

4. In combination, a Bunsen burner having slot-like ports, and radiants supported above the ports, the end walls of the ports converging outwardly so as to direct the 45 gas away from the walls of the radiants.

5. In combination, a Bunsen burner having a plurality of pairs of ports, the axes of the ports of each pair converging upwardly and intersecting on a vertical line 50 that is substantially central of the ports and perpendicular to the plane of the outlet ends thereof, and a radiant supported above each pair of ports and spaced from the burner to provide a secondary air space between the lower end of the radiant and the burner.

6. In combination, a Bunsen burner having a plurality of pairs of ports, the axes of the ports of each pair converging upwardly and intersecting on a vertical line 55 that is substantially central of the ports and perpendicular to the plane of the outlet ends thereof, and a radiant supported above each pair of ports and spaced from the burner to provide a secondary air space between the

lower end of the radiant and the burner, the burner having a secondary air passageway between the ports of each pair.

7. In combination, a Bunsen burner comprising two hollow substantially parallel branches connected together for intercommunication, each branch having a series of slot-like ports, those of one branch being opposite those of the other and the corresponding ports of the two branches constituting a pair of ports, the space between the branches serving as a secondary air passageway, a radiant supported above each pair of ports and spaced from the burner to provide a secondary air space between the lower end of the radiant and the burner, the axes of the ports of each pair converging upwardly and intersecting centrally within the lower portion of the radiant.

8. In combination, a Bunsen burner comprising two hollow substantially parallel branches connected together and communicating at their ends, a mixing tube leading into one end of the burner, each branch having a series of slot-like ports, those of one branch being opposite those of the other and the corresponding ports of the two branches constituting a pair of ports, a radiant supported above each pair of ports and having its lower end spaced from the burner to provide a secondary air space between the lower end of the radiant and the burner, the space between the two branches serving as a secondary air passageway, the axes of the ports of each pair converging upwardly and intersecting centrally within the lower portion of the corresponding radiant.

9. In combination, a Bunsen burner comprising two hollow substantially parallel and relatively close together branches connected and communicating at their ends, a mixing tube leading into one end of the burner, each branch having a series of slot-like ports, those of one branch being opposite those of the other and the corresponding ports of the two branches constituting a pair of ports, a radiant supported above each pair of ports and having its lower end spaced from the burner to provide a secondary air space between the lower end of the radiant and the burner, the space between the two branches serving as a secondary air passageway, the axes of the ports of each pair converging upwardly and intersecting centrally within the lower portion of the corresponding radiant, a gas supply member arranged to discharge into the mixing tube, a valve for controlling the supply, and an auxiliary valve for adjusting the gas emitting orifice of the supply member.

10. In combination, a Bunsen burner comprising two hollow substantially parallel branches connected together and communicating at their ends, a mixing tube leading

into one end of the burner, each branch having a series of slot-like ports, those of one branch being opposite those of the other and the corresponding ports of the two branches constituting a pair of ports, a radiant supported above each pair of ports and having its lower end spaced from the burner to provide a secondary air space between the lower end of the radiant and the burner, the space between the two branches serving as a secondary air passageway, the axes of the ports of each pair converging upwardly and intersecting centrally within the lower portion of the corresponding radiant, a gas supply member arranged to discharge into the mixing tube, a valve for controlling the supply, an auxiliary valve for adjusting the gas emitting orifice of the supply member, and an adjustable air shutter for controlling the primary air supply of the mixing tube.

11. In combination, a Bunsen gas burner comprising two hollow branches joined together at their ends to form a continuous

gas passage and separated by a narrow unobstructed secondary air space, each branch having a series of ports, those of one branch being opposite those of the other and the corresponding ports of the two branches constituting a pair of ports, the ports of each pair being inclined upwardly toward each other so that the flames therefrom meet above the aforesaid secondary air space to form a single flame, and a radiant supported above each pair of ports and in spaced relation to the burner so as to provide a secondary air supply between the lower end of each radiant and the burner.

12. In combination, a Bunsen burner having a plurality of ports and a secondary air space between adjacent ports, and a radiant supported above said ports, said radiant having secondary air openings in the vicinity of the ports.

In testimony whereof, I hereunto affix my signature.

GEORGE E. BENNITT.
